UNITED STATES PATENT OFFICE.

JOHN M. GREGORY, OF SKANEATELES, NEW YORK.

CABBAGE-TRIMMER.

1,091,213.

Specification of Letters Patent. Patented Mar. 24, 1914.

Application filed April 3, 1913. Serial No. 758,688.

To all whom it may concern:

Be it known that I, JOHN M. GREGORY, a citizen of the United States, residing at Skaneateles, in the county of Onondaga and 5 State of New York, have invented certain new and useful Improvements in Cabbage- Trimmers, of which the following is a specification, reference being had therein to the accompanying drawing.

10 This invention relates to certain new and useful improvements in cabbage trimmers; the object being to provide a device by means of which, the wilted leaves of a cabbage can be quickly cut off, and at the same 15 time the stem severed whereby the cabbage can be readily placed in condition for sale; thereby overcoming the difficulties now existing with devices of this character.

Another object of my invention is to provide 20 a device which is so constructed that the same can be adjusted whereby any number of leaves can be cut off.

Another object of my invention is to provide 25 a stem-cutting knife in connection with the leaf-cutting knife which is operated by a treadle at the completion of the cutting of the leaves, thereby facilitating the trimming of a cabbage.

Another and further object of the invention 30 is to provide a device which is exceedingly simple and cheap in construction, and one in which the parts are so mounted that all danger of the same getting out of order is prevented; the leaves and stems falling 35 away from the cutting devices as they are severed from the cabbage.

Other and further objects and advantages 40 of the invention will be hereinafter set forth and the novel features thereof defined by the appended claims.

In the drawings—Figure 1, is a side elevation of my improved cabbage trimmer showing the stem-cutting knife forced into operative position so as to cut off the stem of 45 the cabbage; Fig. 2, is a top plan; Fig. 3, is a vertical transverse section through the upper portion of the trimmer; and Fig. 4, is a detail enlarged section taken on the line 4—4 of Fig. 3, showing the manner of holding the table in its adjusted position.

Like numerals of reference refer to like parts in the several figures of the drawings.

In carrying out my improved invention, I employ a set of legs 1 which terminate at their upper end in a cylindrical portion 2 in 55 which is mounted a cylindrical portion 3 of a frame 4 which is provided with a forwardly projecting tubular portion 5. Mounted within the upper end of the tubular portion 5 of the frame 4 is a cylindrical 60 knife 6 which is held in position therein by screws 7 as clearly shown; and said tubular portion is preferably annularly reduced as shown at 8 to receive the cylindrical knife 6 in order to prevent the same from moving 65 downwardly by the pressure exerted thereon, as will be later described.

Mounted on the tubular portion 5 is a circular table 9 which partially surrounds the tubular portion 5 and is provided with 70 interrupted threads 13 adapted to co-act with interrupted threads 14 formed on the tubular portion 5 so that by revolving the table so as to throw the threads out of contact with each other, the table can be raised 75 and lowered so as to adjust the same vertically in respect to the cutting edge of the knife 6 whereby the number of leaves severed from the cabbage can be regulated by adjusting the table. In order to provide 80 means for preventing the table from being rotated accidentally after the same has been adjusted in its proper position, I provide a set screw 11 mounted in a threaded bore formed in the table and adapted to engage 85 the tubular portion 5 for holding the same in a rigid position.

The frame 4 is provided with a guide-way 15 in which is slidably mounted a blade- carrying member 16 having a depending bifurcated lug 17 into which extends an anti-friction roller 18 mounted upon a pin 19 projecting laterally from the end of a lever 20 which is pivotally mounted in the frame 4 as shown at 21 and is provided with an 95 arm 22 to which the upper end of an operating rod 23 is pivotally connected; said rod having its lower end pivotally connected at 24 to a treadle 25 carried by one of the legs as shown at 26, whereby the knife-carrying 100 member will be moved forward by a pressure being exerted upon the treadle 25.

In order to hold the blade-carrying member in withdrawn position, I provide the

pivoted pin of the lever 20 with a coil spring 27; one end of which engages the frame 4 and the other the arm 22 of the lever 20, so that after the treadle is depressed by the operator's foot and released, the operating rod will be drawn upwardly so as to force the knife-carrying member away from the cylindrical knife of the trimmer. The cylindrical knife of the trimmer is provided 10 with a slot 28 adjacent the cutting edge thereof through which is adapted to extend a blade 29 secured upon the blade-carrying member 16; said blade preferably having a rounded cutting edge 30, as clearly shown in 15 Fig. 2.

In order to provide means for adjusting the forward movement of the blade 29 in respect to the cylindrical cutter 6, I provide the depending lug 17 of the blade-carrying 20 member 16 with a stop screw 31 adapted to be engaged by the tubular portion 5, and it will be seen that by adjusting the screw 31, the forward movement of the blade-carrying member can be regulated in order to prevent 25 the cutting edge 30 of the blade 29 from coming into contact with the opposite wall of the cylindrical cutter 6, thereby preventing the dulling of the blade 29.

The circular table 9 is preferably cut away 30 as shown upon the side of the frame 4 in order to allow the same to be adjusted vertically without interfering with the blade 29 and the blade-carrying member 16.

The operation of the cabbage trimmer 35 constructed as herein shown and described, is as follows: The table 9 is adjusted upon the tubular portion 5 of the frame 4, by first rotating the table slightly and moving the same vertically and then by returning the 40 table to its original position, the threads will be thrown into mesh so as to prevent the table from yielding when pressure is brought to bear thereon and after it has been adjusted in this manner, the set screw 11 is moved 45 into engagement with the tubular portion 5 so as to hold the table in its adjusted position, at the desired distance from the cutting edge of the cylindrical knife 6, and by placing a cabbage upon the cutting edge of the 50 knife and exerting a pressure thereon, the cabbage will be forced downwardly into the cylindrical knife in such a manner that the outside leaves will be severed until the body of the cabbage engages the table 9; the leaves 55 falling off the table, and while I have not shown any receptacle for catching the same, a suitable receptacle may be provided for this purpose, if desired. The operator then 60 presses upon the treadle 25 causing the lever 20 to rock upon its pivot 21, the antifriction roller 18 traveling in the bifurcated lug 17 of the blade-carrying member 16 which causes the member to move forwardly, forc-

ing the blade 29 through the slot 28 of the cylindrical knife 6, and severs the stem of 65 the cabbage which drops out through the tubular portion 5 and likewise can be deposited into any suitable receptacle. The cabbage is then removed and is in such a condition that all of the withered leaves are 70 removed and the stem is neatly trimmed.

It will be seen from the above description that a cabbage can be quickly trimmed and the stem removed by an operator, as it is only necessary to place the cabbage upon the 75 cylindrical knife and exert a slight pressure downward upon the same to remove the leaves therefrom evenly around the body of the cabbage, and after this has been completed, a slight pressure upon a treadle cuts 80 the stem off closely against the body.

While I have shown and described a particular construction of operating the blade in connection with the cylindrical knife and for regulating the number of leaves cut 85 from a cabbage, it is of course understood that various other means may be employed for accomplishing this result such as adjusting the cylindrical knife instead of the table in order to regulate the number of leaves 90 severed and that other mechanism for reciprocating the blade for severing the stem can be substituted without departing from the spirit of my invention.

I claim:

1. A cabbage trimmer comprising a cylindrical cutting member, and a reciprocating blade working transversely through said cylindrical cutting member.
2. A cabbage trimmer comprising a cylindrical cutting member, and an adjustable table surrounding said cutting member.
3. A cabbage trimmer comprising a cylindrical cutting member, a blade adapted to traverse said cylindrical cutting member, 105 and means for operating said blade.
4. A cabbage trimmer comprising a cylindrical cutting member, and means for regulating the depth of cut of said member.
5. A cabbage trimmer comprising a frame, 110 a cylindrical cutting member carried by said frame, a movable table surrounding said cutting member, and means for locking said table in adjusted position.
6. A cabbage trimmer comprising a frame 115 having a tubular portion, a cylindrical knife carried by said tubular portion, a table surrounding said tubular portion, means for holding said table in adjusted position, and a cutting blade adapted to traverse said 120 knife.
7. A cabbage trimmer comprising a cylindrical knife adapted to sever the leaves of the cabbage, means for regulating the number of leaves severed by said cutting knife, 125 and a blade adapted to traverse said knife.

8. A cabbage trimmer comprising a frame, legs for supporting said frame, a cylindrical knife carried by said frame, a reciprocating blade mounted in said frame adapted to traverse said knife, a lever for reciprocating said blade, and a treadle for operating said lever. 65
9. A cabbage trimmer comprising a frame having a tubular portion, a cylindrical knife mounted in said tubular portion having a slot adjacent the cutting edge thereof, a guideway formed in said frame, a blade-carrying member mounted in said guideway, a blade carried by said member extending into said slot of the knife, a lever for reciprocating said blade-carrying member, and a treadle for operating said lever. 70
10. A cabbage trimmer having a cylindrical knife provided with a slotted wall, a blade-carrying member, a blade carried by said member extending into the slot of said knife, an adjustable stop carried by said blade-carrying member for limiting the movement thereof, and means for reciprocating said blade-carrying member. 75
11. A cabbage trimmer comprising a frame having a tubular portion, legs for supporting said frame, a cylindrical knife mounted in said tubular portion, a guideway formed in said frame, a blade-carrying member slidably mounted in said guideway having a bifurcated depending lug, a blade carried by said member extending into the slot of the knife, a pivoted lever mounted in said frame, a laterally projecting member carried by said lever extending into the bifurcated lug of said blade-carrying member, a treadle for moving said lever in one direction, and a spring for returning said lever to its original position. 80
12. A cabbage trimmer comprising a vertically arranged cylindrical knife having a cutting edge at its upper end, said knife being provided with a slot, a reciprocating blade extending into said slot, means for holding said blade in withdrawn position, and means for reciprocating said blade across said cylindrical knife. 85
13. A cabbage trimmer comprising a frame, legs for supporting said frame, a guideway formed in said frame, a tubular portion formed in said frame, a cylindrical knife mounted in the tubular portion, a blade-carrying member mounted in the guideway, said cylindrical knife having a slot, a blade carried by said blade-carrying member extending into said slot, means for reciprocating said blade-carrying member, a table slidably mounted upon said tubular portion of said frame, and means for holding said table in adjusted position. 95
14. A cabbage trimmer comprising a tubular support having interrupted threads, a cylindrical blade carried by said support, a table embracing said tubular support provided with interrupted threads co-acting with the threads of the support, and means for preventing said table from moving in respect to said support. 100
15. A cabbage trimmer comprising a frame having a tubular member, a cylindrical cutting knife arranged within said member having a slotted wall adjacent its cutting edge, a guideway formed on said frame, a blade-carrying member slidably mounted in said guideway, a blade carried by said member extending into the slot of said cylindrical knife, an adjustable stop carried by said blade-carrying member adapted to engage said tubular portion, manually operated means for moving said blade-carrying member in one direction, and means for returning said blade to original position. 105
16. A cabbage trimmer comprising a leg-supported frame, a cylindrical cutting knife carried by said frame having a slotted wall, a reciprocating blade extending into the slot of said wall, an oscillating member for reciprocating said blade, and a treadle for oscillating said oscillating member. 90
17. A cabbage trimmer comprising a leg-supported frame having a tubular portion carrying a cylindrical blade, an adjustable table mounted on said tubular portion, said cylindrical blade being provided with a slot, a spring-actuated reciprocating blade extending into said slot, a lever mounted in said frame for reciprocating said blade, a spring-actuated rod connected to said lever, and a treadle connected to said rod for causing said blade to traverse said knife. 95
18. A cabbage trimmer comprising a leg-supported frame having a laterally projecting tubular portion, a cylindrical knife arranged within said tubular portion having a slot adjacent the cutting edge thereof, a guideway formed on said frame, a blade-carrying member mounted in said guideway, a blade carried by said member extending into the slot of said knife, a depending bifurcated lug carried by said blade-carrying member, a spring-actuated lever mounted in said frame having a laterally projecting pin having an anti-friction roller extending into said bifurcated lug, an arm formed on said lever, an operating rod connected to said arm, and a treadle connected to the lower end of said operating rod. 110
19. A cabbage trimmer comprising a set of legs terminating in a cylindrical portion at the upper end thereof, a frame having a cylindrical portion fitting within the cylindrical portion of the legs, a cylindrical knife carried by said frame having a slotted wall, and a reciprocating blade mounted in said frame adapted to extend into said slot and traverse said knife. 115
20. A cabbage trimmer having a cylindri-

cal knife for removing the leaves from the stalk of a cabbage by exerting a pressure upon the cabbage, means for limiting the downward movement of the cabbage in respect to said cutting knife, and a blade adapted to traverse said cutting knife for severing the stalk of the cabbage.

In testimony whereof I affix my signature in presence of two witnesses.

JOHN M. GREGORY.
